DUAL STRING HYDRAULIC PACKER

Morgan L. Crow, Dallas, Tex., assignor to Dresser Industries, Inc., Dallas, Tex., a corporation of Delaware

Filed Jan. 23, 1963, Ser. No. 253,429

16 Claims. (Cl. 166—122)

This invention is concerned with a well packer and is particularly concerned with a well packer which is set by hydraulic pressure, and which may be retrieved from the well.

The packer disclosed herein is of the dual type, having two passages therethrough for communication with separate zones of production in a well.

Previous packers of this type have not been entirely satisfactory, in that it was necessary to provide a tension member within the packer to transfer the setting force between opposite ends of the packer sleeve, thereby necessitating the stretching or moving of the tubing in order to set the packer; it was necessary to rotate the tubing to release the packer, thus disturbing other tools in the well; and it was necessary to telescope the cylinder and piston to running-in position to retrieve the packer, thereby rendering it difficult or impossible to retrieve the packer when the cylinder is compacted with mud or debris found in the well; and no satisfactory means was provided for compensating for additional expansion of the rubber, or preventing upsetting of the rubber, allowing leakage thereby.

The present packer construction is intended to overcome the above recited shortcomings in prior packers of this type, and accomplish other objects, among which are the following:

The packer is anchored for setting by hydraulic anchors at the upper end of the packer assembly in such a manner that the casing serves as a tension member in setting, thereby permitting positive location of the tubing and eliminating the necessity that the tubing be moved or stretched in setting the packer, thereby assuring that other tools already set in the well, such as packers or other tools therebelow, will not be disturbed upon setting the packer.

The packer sleeve is held in expanded position by mechanical slips inside the packer, eliminating hydraulic pressure traps and the necessity for check valves.

Retrievability is made easier in that no rotation is required to release the packer. The packer may be released for retrieval by a simple upwardly exerted force on the tubing string which releases same at a predetermined pull.

It is not necessary to telescope the cylinder and piston to running-in position to release the packer. Therefore, debris and mud which might accumulate in the cylinder do not affect retrievability.

The hydraulic cylinder and piston are located above the packer rubber which permits direct downwardly acting force on the packer rubber in setting.

Mechanical take-up slips located inside the packer improve the pack-off and locks in increased expansion of the packer rubber by reason of reversal of pressure across the packer.

Internal slips inside the packer which are set by mechanical means, positively hold the packer in set position and may be positively retracted when pulling to permit full length relaxation of the packer sleeves.

Fluid by-pass is provided upon removal of the second tubing string which is equivalent to the tubing area to provide ease in retrieving the packer.

The hydraulic anchors at the upper end of the packer grip the casing to initially hold the packer while it is being set, and also hold the packer against upward pressure from below after the packer is set.

Other and further objects of the invention will become apparent upon reading the detailed specification hereinafter following, and by referring to the drawings annexed hereto.

5 A suitable embodiment of the invention is shown in the attached drawings, wherein:

FIGURES I, I-A, and I-B show a cross-sectional, elevational view of the packer assembly incorporating the improvements described and claimed herein;

10 FIGURES II, II-A and II-B show a cross-sectional, elevational view taken on the line II-II of FIGURES I, I-A and I-B;

FIGURE III is a cross-sectional, elevational view in semi-diagrammatic form illustrating the position of the 15 various parts of the packer assembly in set position in the casing;

FIGURE IV is a view similar to FIGURE III, but showing the relative positions of the parts of the packer assembly after it has been relaxed for retrieval from the 20 well;

FIGURE V is a transverse, sectional view taken on the line V-V of FIGURE I;

FIGURE VI is a transverse, sectional view taken on the line VI-VI of FIGURE I;

25 FIGURE VII is a transverse, sectional view taken on the line VII-VII of FIGURE I-A;

FIGURE VIII is a transverse, sectional view taken on the line VIII-VIII of FIGURE I-A;

FIGURE IX is a transverse, sectional view taken along 30 the line IX-IX of FIGURE I-A;

FIGURE X is a transverse, sectional view taken along the line X-X of FIGURE I-A;

FIGURE XI is a transverse, sectional view taken along the line XI-XI of FIGURE I-A;

35 FIGURE XII is a transverse, sectional view taken along the line XII-XII of FIGURE I-B; and

FIGURE XIII is a perspective exploded view of the 40 spring carrier, slip pick-up, slip guide, slip rest bodies and slip bodies assembly.

Numeral references are employed to designate the various parts shown in the drawings, and like numerals indicate like parts throughout the various figures of the drawings.

The numeral 1 indicates an entry scoop which has 45 concical entry surface 1a therein to guide the stinger on the secondary tubing string into the secondary passage for latching same therein.

The entry scoop has parallel passages 2 and 3 provided therethrough, which are in alignment with the passages 50 through the packer, as will be hereinafter described.

The entry scoop 1 is secured to the anchor body 5 by means of cap screws 1b and 1c.

The anchor body 5 has parallel passages 5a and 5b therethrough, the passage 5b having a locking rib 5c therein arranged to receive and lock in place resilient lugs or prongs on a stinger attached to the secondary string so that the stinger may be latched in the passage 5b after the packer has been run.

60 The packer is attached to, and may be run into the well, on a primary tubing string 4 which is threadedly engaged in the upper end of the passage 5a by means of complementary threads 4a.

Referring to FIGURES II and VI, the hydraulic anchor body has a plurality of anchor slip pistons 6 mounted thereon which are slidably disposed in bores 6a in the wall of the anchor body.

65 The slips are slidably and sealingly engaged with the wall of the bores 6a by means of seal rings 6b, and are biased inwardly by means of springs 6c which are abutted against retainer strips 6d which pass through longitudinal grooves 6f on the outer surface of the slip teeth. The

strips **6d** are mounted on the body **5** by means of screws **6e**.

The piston slips **6** are actuated and moved outwardly by means of hydraulic pressure exerted through the secondary tubing string **61** which passes through the ports **7** which communicate with connected passages **7a** behind the pistons.

The stationary piston or back-up **8** is secured to the lower end of the anchor body **5** by means of a threaded connection collar **9** which has a flange on the lower end thereof engageable with a shoulder on the upper end of the piston **8**, and is threaded to the lower end of the anchor body **5**. An appropriate seal is provided between the connection collar **9** and the anchor body **5**. The piston **8** could be made integral with anchor body **5**, and in fact the body **5** and piston **8** can be considered as one body herein.

Primary and secondary seal sleeves **10** and **11** are positioned between the aligned bores through the anchor body **5** and piston **8**, said seal sleeves having resilient O-rings **10a** and **11a** positioned thereabout to provide appropriate seals about said passages.

A hollow cylinder **12** is slidably disposed about the piston **8**, and an O-ring seal **13** is disposed in an appropriate channel about the piston **8** and sealingly and slidably contacts the inner wall of the cylinder **12** to provide a seal therebetween.

The piston **8** and the cylinder **12** are initially frangibly secured together by means of a shear screw **14** passing through the wall of the cylinder **12** and into the wall of the piston **8**.

The primary mandrel or support **15** is threadedly engaged at the lower end of the primary passage **8a** through the piston **8** by means of threads **15a**; and the secondary mandrel, or tubular support **16**, is attached in communication with the secondary passage **8b** by means of appropriate threads **16a**.

The mandrels **15** and **16** extend entirely through the packer rubber assembly, and provide the primary supports therefor.

O-ring seals **17** and **17a** provide slidable seals between mandrels **15** and **16**, and the passages through the lower ends of the cylinder **12**.

A mandrel slip support ring **18** has parallel passages therethrough and is disposed about the mandrels **15** and **16**, and is attached to the mandrel slip housing **19** by means of screws **18a**. The mandrel slip housing **19** is surrounded by a support sleeve **19c** which interlocks with the support ring **18**, and has downwardly tapered parallel passages **19a** and **19b** therethrough to receive the mandrels **15** and **16**. There are disposed in the tapered passages a plurality of slips **20** which are guided and held in alignment by guide pins **21** extending inwardly of passages **19a** and **19b** into slots **20a** in the outer faces of slips **20**.

The slips **20** have inner upwardly directed teeth thereon arranged to bite into the outer walls of the mandrels **15** and **16** when force is applied thereto in the manner hereinafter described.

The slip bodies **20** have tapered surfaces on the outer sides thereof which are arranged to seat against the corresponding tapered surfaces in the passages **19a** and **19b** through the mandrel slip housing **19**, and the tapered surfaces are maintained in contact by means of springs **22**, which are seated in sockets **20b** provided in the upper surfaces of slip bodies **20** and against the lower face of the support ring **18**.

The spring carrier housing **23** has parallel passages therethrough to receive the mandrels **15** and **16**, and is attached to the slip guide **25** by means of a plurality of tie bolts **24** which extend through vertical bores in the wall of housing **23** and are threadedly engaged in threaded vertical bores provided in the upper ends of the spaced sides **25a** and **25b** of slip guide **25**. Set screws **23a** attach spring carrier **23** to secondary mandrel **16**.

A slip pick-up **27** is disposed between the mandrels **15** and **16** and the slip guide is initially attached to the mandrels **15** and **16** by means of set screws **25c**, which slide on the mandrels when the packer is set. The tubular mandrels **15** and **16** extend on opposite sides of the slip pick-up **27** and within the slip guide **25** (see FIGS. VJII and IX).

The slip guide **25** has spaced sides **25a** and **25b** between which are slidably disposed slip rest bodies **28** which are engaged thereto by flanges **28c** thereon. The lower end of slip guide **25** has closed sides **25d**. The slip bodies **26** are slidably connected to slip rest bodies **28** by slide dovetail connections, as indicated at **26a** and the lower end of the slip pick-up **27** has inwardly tapered shoulders **30** thereon against which the slip rest bodies **28** are seated on corresponding tapered shoulders **28a** thereon, and are slidably connected thereto by a dovetail connection, indicated at **28b** (FIG. IX).

The slip rest bodies **28** are frangibly secured to the slips **26** by means of shear pins **31**, and are connected to the slip guide **25** by means of guide pins **32** which pass through the elongated slots **33** provided therethrough and through aligned holes in the walls of the guide **25**. The guide pins **32** are retained in place by such screws **32a** threaded into the holes through the wall of slip guide **25**. The slip rest bodies **28** act as expanders for slips **26**, and are moved and held outward by the tapered surfaces **28a** on slip rest bodies **28** and **30** on pick-up head **27**.

It will be seen that the slip rests **28** are permitted to move inwardly and outwardly on the guide pins **32** by virtue of the elongated slots **33** when pick-up head **27** is moved up and down. However, it will be observed that slips **26** cannot release until pick-up head **27** is lifted up with relation to the bodies **28**, thus assuring that the packer cannot release until the primary mandrel is pulled upwardly from the surface.

Slip follower pins **23b** are positioned in bores **23c** provided through the spring carrier housing **23**, and are urged downwardly by means of springs **23a** disposed in said bores thereabove, which are held therein by means of screws **23d** threaded into the upper ends of said bores.

The lower ends of the slip follow pins **23b** are positioned against the upper ends of the slip bodies **26** and the springs **23a** cause same to urge the slips downwardly along the contacting tapered surfaces between the slips and the slip rests **28** so as to urge the slips outwardly toward the wall of the casing **65** when the frangible pins **31** are broken.

The slip bodies **26** have upwardly directed teeth on the outer surfaces thereon which are arranged to bitingly engage the inner wall of the casing **65** to anchor same thereto.

Downwardly facing pickup shoulders **35** are provided within the slip pick-up **27**, which are arranged to come into contact with the pick-up shoulder **34** on the primary mandrel **15** (FIGS. III and IV), to lift the slip pick-up **27** upwardly to permit the inward movement of the slip rests **28**, to thereby release the slips **26** in the manner which will be hereinafter described.

When slip pick-up **27** thus moves upwardly upon relaxation and retrieval of the packer, shoulders **36** on opposite sides of slip pick-up **27** engages a shoulder **36a** on the spring housing **23** to lift the spring housing upwardly and allow slips **26** to move inwardly to release same for retrieval from the well.

A plurality of packer sleeves **37**, having aligned parallel passages therethrough to receive the mandrels **15** and **16**, are separated by spacer plates **38** and supported at each end by end support plates **39**. Upper support plate **39** is attached to the lower end of slip guide **25**.

A lower expander head **40** is attached to the lower packer support **39** and has parallel passages therethrough to receive the mandrels **15** and **16**.

The expander head **40** has tapered surfaces **40a** thereon which are slidably connected to the inner corresponding

tapered surfaces 41a of the anchor slips 41 by means of a dovetail connection indicated at 42.

The expander head 40 is secured to the primary mandrel 15 by means of set screws 43.

A slip carrier 44, having parallel passages therethrough to receive the mandrels 15 and 16, has slip retainers 44a attached to flat surfaces on the outer sides thereof, by means of screws 45. The slip carriers 44 support the slip bodies 41 by means of slideable connections therebetween so that the slip bodies 41 may move outwardly with relation thereto by reason of relative slideable movement between the tapered surfaces 41a and 40a. The slip support assembly just described is frangibly secured to the secondary mandrel 16 by means of a shear pin housing 46 attached to the slip carrier 44 by means of screws 47, which shear pin housing is frangibly secured to the secondary mandrel 16 by means of shear pins 48 (FIG. XII).

A downwardly facing pick-up shoulder 49 is provided in the secondary passage through the expander heads 40, which is arranged to contact a pick-up shoulder 50 provided on the secondary mandrel 16 to retrieve the packer assembly out of the well after breaking the shear pins 48 and relaxing the packer in the manner hereinafter described.

A seating sub 51 is attached to the lower end of the secondary mandrel 16 by means of a sub 52 which in turn is attached to the secondary mandrel by means of a coupling 53. The seating sub 51 is attached to the sub 52 through a coupling 54.

A shearable seat 55 is provided in the bore of the seating sub 51, said seat being arranged to receive a valve ball 55a which is dropped into the secondary tubing and allowed to gravitate to a position of rest on the expellable seat 55 in order to permit the application of hydraulic pressure to the piston in the packer for setting, in the manner hereinafter described.

The expellable seat 55 is frangibly secured within the seating sub 51 by means of a shear ring 56, which has a reduced thickness on the outer edge thereof clamped between the inner end of the shear ring retainer 57 and a downwardly facing shoulder within the seating sub 51.

A section of tubing is attached to the primary mandrel 15 by means of a sub 59 and a coupling 60. The tubing 58 would extend below the packer assembly herein described, and would be connected to another packer at a lower level in the well.

After the packer assembly has been lowered into the well to the desired position where it is to be set, the secondary string of tubing 61 may be run into the well and latched into the secondary passage provided through the anchor body 5 by means of a seal stinger 62, which for convenience, is shown as having a detachable connection, consisting of a J-slot 63 which engages a pin 64 in the secondary passage 3. Other types of disengageable latching stingers may be employed than the one shown, which is merely illustrative of a suitable form.

The operation and function of the hydraulic packer device hereinbefore described is as follows:

The packer is assembled and lowered into the well on the primary tubing string 4. Usually there is a single bore packer already set in the well below the dual bore packer, and the tubing string 58, extending therebelow, is guided into, and latched in, the upper end of the bore of such packer. The secondary string 61 is then made up and run into the well and the stinger 62 thereof is guided into the secondary bore 5b of the anchor body 5 through the tapered surface 1a of the entry scoop 1, where it is latched in place by means of the J-slot arrangement shown, or otherwise.

The valve ball 55a is then released into the secondary tubing string 61 and allowed to gravitate downwardly to come to rest upon the expellable seat member 55. Hydraulic pressure is then increased in the secondary string to move the piston slips 6 outwardly by pressure released

therebehind through the passages 7 and 7a. Thus the packer assembly is anchored to the casing by means of the hydraulic slips 6.

Increased hydraulic pressure through the secondary tubing string 61, and through port 12a through the wall of mandrel 16, breaks the cylinder shear pins 14, releasing the cylinder 12. The cylinder 12 then moves downwardly, which shears the shear pins 31 holding the cinch slips 26 to the slip rests 28, which allows relative slideable movement therebetween along the tapered surfaces. The slip follower pins 23b maintain the cinch slips 26 downwardly and outwardly in engagement with the wall of the casing. A continued downward movement of the cylinder 12 moves the mandrel slip retainer 18, mandrel slip housing 19, spring carrier 23, and slip guide 25 downwardly, applying force against the packer rubbers 37. The packer rubbers 37 move downwardly about the mandrels 15 and 16, and thereby move the expander head 40 downwardly to expand the slip bodies 41 outwardly into anchoring engagement with the casing.

Further downward movement of cylinder 12 compresses and expands the packer rubbers 37 into sealing engagement with the wall of the casing, and anchors 25 the slips 41 into biting engagement with the wall of the casing.

It will be noticed during this operation that the casing is used as a tension member in setting the rubber in compression. The lower slips 41 support the rubber 30 and the reaction from the piston 8 and cylinder 12 is carried through the hydraulic anchors 6 into the casing.

The mandrel slips 20 are urged into engagement with the mandrels 15 and 16 while the packer is being set, and the upwardly directed teeth thereon bite into the walls of the mandrels after the packer is set and resists any tendency of the packer sleeves to relax in an upward direction since they are locked by the slip bodies 20 against upward movement. Thereby the mandrel slips 20 maintain the slip pick-up 27 in set position and prevent the slips 26 from becoming unset. Any additional weight imposed upon the tubing strings will be transmitted to the rubbers 37 through the slips 20 and 26, and any additional compression of the rubber by such added weight will be locked into the rubber by the slips 26.

The slips 20 are inside the packer in protected position so that debris and well mud do not effect their operation.

To retrieve the packer from the well, it is not required to rotate same to release the packer. It is necessary only to exert an upstrain on the primary tubing string 4 after the secondary string 61 has been disengaged from the packer.

It will thus be noted that the cylinder 12 and piston 8 do not have to be telescoped into running-in position in order to retrieve the packer. Neither do the mandrel slips 20 need to be released in order to pull the packer. The secondary string 61 may actually be left in place while the packer is being released. However, it is advisable to release the secondary string from the packer before retrieving in order to provide a fluid by-pass through the secondary mandrel 16 while retrieving.

Continued upstrain on the primary tubing string will shear the shear pins 48 holding the primary mandrel 15 down. As the anchor body 5, piston 8, and mandrels 15 and 16 move up, the shoulder 34 on the primary mandrel engages the shoulder 35 in the slip pick-up 27, and lifts the slip pick-up upwardly, allowing the slip retainers 28 to move inwardly by reason of the separation of the conical shoulders thereon and on the slip pick-up, thereby allowing the slips 26 to retract and move inwardly. As the slip pick-up 27 moves upwardly, the shoulders 36 thereon engage shoulders 36a in the spring housing 23 and pick it up, thereby allowing the cinch slip 26 and assembly to be pulled out of the well in re-

laxed condition. The cinch slip assembly is retrieved from the well in relaxed position suspended on the shoulder 34 on the primary mandrel.

The shoulder 50 on the secondary mandrel engages the shoulder 49 and picks up the expander head 40, thereby releasing the slips 41 from the casing and the packer may thus be retrieved from the well in fully relaxed condition.

It will be noted that the same relative motion between piston 8 and cylinder 12 is present in setting and releasing the packer so that the parts do not have to be re-telescoped to release and retrieve the packer.

It will, therefore, be seen that I have provided a dual bore hydraulic packer in which the casing is used as a tension member, no rotation is required to set or unset same, the tubing does not have to be moved or stretched in order to set the packer, it is set by positive hydraulic action, slip means are provided inside the packer for compensating and locking in additional force and compression applied to the packer rubbers, positive means is provided for unlatching the packer for retrieval from the well, and the piston and cylinder do not have to be retelescoped for retrieval.

It will be understood that other and further embodiments of my invention may be made without departing from the spirit and scope of the appended claims.

Having described my invention, I claim:

1. In a packer device, a body having parallel longitudinal passages therethrough; hydraulically actuated slips mounted in the wall of the body arranged to be moved outwardly thereof into engagement with a surrounding well casing; means for supplying hydraulic pressure from one of the passages to the inner ends of the hydraulically actuated slips; a pair of tubular mandrels attached in the passages through the body and suspended therebelow; a hydraulic cylinder slidably and sealingly disposed about the mandrels and sealingly and slidably engaging the outer wall of the body and arranged to move downwardly in response to hydraulic pressure; means for supplying hydraulic pressure from one of said passages to the hydraulic cylinder to move same downwardly; at least one packer sleeve disposed about the mandrels and slidably disposed thereon; slip means arranged about the mandrels between the cylinder and the packer sleeve; said slip means having upwardly directed teeth on the inner sides thereof engageable with the outer walls of the mandrels; guide means between the cylinder and slip means; co-acting conical surfaces on the slip means and the guide means to move the slips inwardly; anchor slips below the packer sleeve; an expander head arranged about the mandrels to urge the anchor slips outwardly against the wall of a surrounding well casing; frangible means securing the anchor slips to one of the mandrels; and shoulder means on one of the mandrels engageable with shoulder means in the expander head to lift same upwardly when the frangible means is broken.

2. The combination called for in claim 1 with the addition of additional slip means between the cylinder and the packer sleeve, said slip means having outer, upwardly directed teeth arranged to engage the wall of a surrounding well casing; expander means within the said slip means arranged to urge the slip means outwardly; and shoulder means on the other mandrel arranged to engage the expander means for the said slips to lift the expander means upwardly.

3. The combination called for in claim 2 with the addition of guide means slidably attached to the expander means for additional slip means arranged to allow lateral but not vertical movement of the expander means for said additional slip means.

4. The combination called for in claim 2 wherein the additional slip means are frangibly connected to the expander means therefor.

5. In a well packer, a tubular body having a pair of

longitudinal passages therethrough; a pair of tubular mandrels attached in, and extending below, the passages; at least one packer sleeve surrounding the mandrels; a support secured to one of the mandrels below the packer sleeve; slips secured to the support below the sleeve; expander means surrounding the mandrels below the sleeve arranged to move the slips outwardly; hydraulically actuated telescoping members, one of which is stationary and the other of which is movable downwardly against the upper end of the packer sleeve to compress same; means to apply hydraulic pressure from one of the passages between the telescoping members; hydraulically actuated slip pistons mounted in the wall of the body and movable outwardly thereof; and means to apply hydraulic pressure from one of the passages to the inner ends of the hydraulically actuated slip pistons.

6. The combination called for in claim 5 wherein the connection between the support and the mandrel is frangible, and shoulder means is provided on the mandrel engageable with shoulder means in the expander means when the mandrel is moved upwardly.

7. The combination called for in claim 5 with the addition of mandrel engaging means above the packer sleeve having inwardly directed teeth thereon engageable with at least one of the mandrels; and means to urge the teeth into engagement with the mandrel.

8. The combination called for in claim 5 with the addition of a plurality of casing slips above the packer sleeve having upwardly directed teeth on the outer sides thereof movable outwardly; and expander means movable downwardly by the downwardly moving telescoping member to expand the casing slips outwardly.

9. The combination called for in claim 8 wherein the expander means for the casing slips is slidably mounted on guide members to permit lateral but not vertical movement thereof.

10. The combination called for in claim 5 with the addition of a valve cage connected to the lower end of one of the mandrels; and a shearable valve seat attached in the bore of the cage.

11. The combination called for in claim 5 wherein one of the telescoping members is a piston secured to the mandrels and the other is a cylinder slidably and sealingly disposed about the mandrels and about the body arranged to move downwardly against the packer sleeve.

12. In a well packer; a body having a pair of longitudinal passages therethrough; hydraulically actuated piston slips mounted in the wall of the body and movable outwardly thereof; primary and secondary mandrels suspended in said passages, a hydraulically actuated cylinder slidably and sealingly embracing the body, and slidably and sealingly embracing the mandrels; a base member frangibly secured to the secondary mandrel; a plurality of anchor slips attached to the base and being movable outwardly thereof; an expander head slidably disposed about the mandrels; slideable contacting conical surfaces on the head and within the anchor slips; at least one resilient packer sleeve slidably disposed about the mandrels above the expander head; a plurality of mandrel slips surrounding the mandrels below the cylinder and above the packer sleeve, said mandrel slips having teeth on the inner sides thereof arranged to contact the mandrels; means to urge the teeth into contact with the mandrels; a plurality of cinch slips surrounding the mandrels above the packer sleeve, having teeth on the outer sides thereof; a spring housing about the mandrels above the cinch slips; a plurality of spring urged pins movably extending below the spring housing, one of which contacts each cinch slip to urge same downwardly; a pick-up head disposed between the mandrels within the spring housing; a plurality of slip expander bodies disposed between the cinch slips and the pick-up head; co-acting slidably related tapered surfaces on the cinch slips and on the expander bodies arranged to urge the said slips outwardly; frangible means initially

connecting the cinch slips and the expander bodies; and contacting inwardly directed tapered surfaces on the inner sides of the slip expander bodies and on the outer sides of the lower end of the pick-up head.

13. The combination called for in claim 12 with the addition of guide means arranged to permit lateral but not vertical movement of the expander bodies relative to the pick-up head.

14. The combination called for in claim 12 with the addition of shoulder means on the primary mandrel; shoulder means on the pick-up head engageable with the shoulder means on the primary mandrel; shoulder means in the spring housing; additional shoulder means on the pick-up head arranged to engage the shoulder means in the spring housing; shoulder means in the expander head; and shoulder means on the secondary mandrel engageable with the shoulder means in the expander head.

15. The combination called for in claim 12 with the addition of frangible means initially connecting the cylinder to the body.

16. In a well packer, a tubular body having a plurality of longitudinal passages therethrough; a plurality of tubular mandrels attached in, and extending below, the passages; at least one packer sleeve surrounding the mandrels; a support secured to one of the mandrels below the packer sleeve; slips secured to the support below the sleeve; expander means surrounding the man-

drels below the sleeve arranged to move the slips outwardly; hydraulically actuated telescoping members, one of which is stationary and the other of which is movable downwardly against the upper end of the packer sleeve to compress same; means to admit hydraulic pressure from one of said passages between the hydraulically actuated telescoping members; hydraulically actuated slip pistons mounted in the wall of the body and movable outwardly thereof and means to admit hydraulic pressure from one of said passages to the inner ends of said hydraulically actuated slip pistons.
